INVENTOR:
Patrick C. Flanagan
BY
James D. Hamilton
ATTORNEY

UNITED STATES PATENT OFFICE.

PATRICK C. FLANAGAN, OF NEW YORK, N. Y.

INDIVIDUAL PROTECTIVE ARMOR.

1,276,200.

Specification of Letters Patent. Patented Aug. 20, 1918.

Application filed April 3, 1918. Serial No. 226,374.

To all whom it may concern:

Be it known that I, PATRICK C. FLANAGAN, a citizen of the United States of America, residing at the borough of Manhattan, in the city, county, and State of New York, have invented certain new and useful Improvements in Individual Protective Armor, of which the following is a specification, reference being had to the accompanying drawings.

This invention relates to improvements in individual protective armor designed to be worn by a soldier for the purpose of affording him protection on the field of battle and particularly to improvements in the protective armor illustrated and described in Patent No. 1,238,120 granted me August 28, 1917. An object of this invention is to provide armor of the general character described and shown in the aforesaid patent with means by which the parts of the armor are given freedom of movement relatively to the parts of the body of the wearer, and ease of movement and greater protection are afforded to the latter.

In the drawings illustrating the principle of this invention and the best mode now known to me of applying that principle, Figure 1 is a front elevation of the armor; Fig. 2 is a side elevation of the same, parts being shown broken away for sake of clearness of illustration; Fig. 3 is a plan; Fig. 4 is a detail illustrating the mounting of the head-piece or helmet; Fig. 5 is a detail showing the pivotal connection between the shoulder-engaging supporter and the breastplate or body-armor; and Fig. 6 is a detail in perspective of the helmet-supporting band.

The armor consists of two principal parts or members, namely, the headpiece or helmet *a* and the breastplate or body armor *b*; both these parts are made of a specially-prepared metal that combines lightness with resistance to penetration. From the vertical mid-line of the breastplate *b*, each side thereof inclines rearwardly through an angle of about thirty degrees (Fig. 3); and, at the top of each of these sides, the breastplate *b* is formed with a laterally-projecting shoulder-piece *c* that fits over the soldier's shoulder and protects the same. On the inner face of each side of the breastplate *b*, there is arranged vertically a series of looped or bow-shaped leaf-springs *d* which are connected together by an upright strip *e*, whereby the several springs *d* are made

to act in unison and mutually support one another. The parts of the armor described in the foregoing are disclosed in my patent above-mentioned.

The armor is fastened to the soldier's body in the following manner: Over each of the soldier's shoulders, there is fitted a crook-shaped upright supporter *f* the upper end of which is bifurcated. (See Fig. 2). The lowermost branch *g* of the forked upper end of the supporter *f* curves downwardly and inwardly and is free from connection with the breastplate *b*, while the upper branch *h* extends horizontally inward and is formed, at its inner end with an upright pivot-pin *i* which passes through an eye *j* fastened to the inner face of the breastplate *b*. As is shown clearly in Fig. 5, the length of the pivot-pin *i* is sufficiently great to permit of its playing freely up and down in its bearing *j*, while it is, of course, free to turn therein. The upright or leg part of each supporter *f* is formed with a series of eyes *f'* arranged one above the other; and, through these eyes *f'*, are passed horizontally-disposed straps *k* one end of each of which is secured (as at *k'*, Fig. 3) to the inner face of the breastplate *b*, while the other end is engaged by the tongue *m'* of a buckle *m* carried by the outer end of a strap *o* the inner end of which is fastened to the inner face of the breastplate *b* at a point *p* horizontally opposite the point *k'* at which the co-operating strap *k* is attached to the breastplate *b*. By thus mounting the breastplate *b* upon the supporters *f* and securing the latter and the breastplate *b* to the soldier's body, with the cushioning springs *d* interposed between the same and the breastplate *b*, great flexibility is imparted to the armor and the soldier is allowed freedom of movement, while wearing it. The armor will conform to the movements of and the attitudes assumed by the body of the soldier in walking, running, crouching, kneeling, lying flat, discharging his rifle, fighting with his bayonet, throwing hand grenades, hand-to-hand fighting and any other work that so-called "shock" troops may be called upon to perform in raiding, trench warfare or open fighting. Moreover, owing to its mounting, the armor will yield readily to impact, no matter from what direction the blow may fall.

To the top of the breastplate *b*, there is secured a horizontally-disposed ring *q* which

is L-shaped in transverse section (Fig. 2) and serves as a raceway for the balls *r*, upon which rests the annular flange *s* that projects from the bottom of the helmet *a* just below the slits *a'* formed therein and affording to the soldier a view of his surroundings. The helmet *a* is held against removal by means of hooklike projections *t* that engage under the bottom or annular flange *q'* which 10 projects inwardly from the ring *q* and upon which run the balls *r* (Fig. 2). Above the ring *q*, there projects inwardly, from, the upper edge-portion of the breast-plate *b* an annular lip or flange *y* that overlies the flange *s* projecting from the helmet *a*. This flange *y* serves to prevent foreign matter from gaining access to the ball raceway, in the accomplishment of which object, it is aided by the outwardly-projecting flange *s*. 15 In order to relieve the latter of much of the weight of the helmet *a* and to make the rotation of the same as frictionless as may be, the following construction is provided (Fig. 4): Within the helmet *a* and in the crown thereof, there is mounted a piece *u* of antifriction metal formed with recess *u'* at its center; and, into this recess *u'*, there projects the pointed end *v'* of a threaded pivot-pin *v* adjustably mounted in the top of a helmet-supporter *w* of inverted-U or arch shape (Fig. 6). The ends *w'* of the helmet-supporting band *w* embrace the ring *q* and are welded or otherwise securely attached thereto (Figs. 2 and 3). So mounted, the helmet *a* is free to spin 20 around on the pivot-pin *v*.

In my armor hereinbefore described, the supporters *f* are held, by the straps *k*, against the soldier's body and the downwardly-curved branches *g* serve likewise to retain these supporters *f* thereon. By this arrangement of parts, the breastplate *b* is held yieldingly, yet securely, on the soldier and with no greater discomfort, inconvenience or hampering of his movements than 25

would result from the wearing of a comparatively heavy outer garment by him. By fastening the ends of a sling-strap (not shown) to the eyes or loops *x* at the lower edge-portion of the breast-plate *b* and passing the sling-strap over one shoulder and 30 under the arm on his opposite side, the soldier may readily carry his armor without wearing the same.

I claim:

1. An armor of the character described, 35 including a breastplate; supporting devices therefor adapted to pass over the shoulders of the soldier and extend along his back; and means for binding said supporters to the soldier's body; the upper inner ends of said 40 supporters being pivotally attached to said breastplate and of such length as to slide lengthwise in their bearings.

2. An armor of the character described, 45 including a breastplate; supporting devices 50 therefor adapted to pass over the shoulders of the soldier and extend along his back and having forwardly and downwardly curved branches serving to clasp his chest; and means for binding said supporters to the soldier's body; the upper, inner ends of 55 said supporters being separated from said branches and pivotally attached to said breastplate.

3. An armor of the character described, 60 including body armor; a helmet-supporting device supported thereby; and a helmet the top of which is pivotally mounted on said device.

Signed at the borough of Manhattan, city, 65 county and State of New York, this twenty-seventh day of March, A. D. 1918, in the presence of the two undersigned witnesses.

PATRICK C. FLANAGAN.

Witnesses:

GEORGE E. BROWN,
JAMES HAMILTON,
